JBL Endurance DIVE headphones, no date available [online], [retrieved May 22, 2019]. Available from Internet, URL: <https://www.ishopchangi.com/product/jbl-endurance-dive-wireless-sports-headphones-with-mp3-player-35587/19>.*Primary Examiner — Barbara Fox*Assistant Examiner* — Mary Claire Ramirez(74) *Attorney, Agent, or Firm* — Plumsea Law Group, LLC(57) **CLAIM**

The ornamental design for a headphone, as shown and described.

DESCRIPTION

FIG. 1 is a perspective view of a headphone showing the new design;

FIG. 2 is a front elevational view thereof;

FIG. 3 is a rear elevational view thereof;

FIG. 4 is a top view thereof;

FIG. 5 is a bottom view thereof;

FIG. 6 is a side elevational view thereof; and,

FIG. 7 is an opposite side elevational view thereof.
The claim encompasses the mirror image embodiment thereof.

The broken lines shown in the drawings depict portions of the headphone that form no part of the claimed design.

1 Claim, 5 Drawing Sheets(56)
